Attorney

UNITED STATES PATENT OFFICE.

HERMAN D. KUHLMAN, OF OMAHA, NEBRASKA.

LUBRICATOR.

1,331,651.

Specification of Letters Patent.

Patented Feb. 24, 1920.

Application filed August 2, 1919. Serial No. 314,877.

To all whom it may concern:

Be it known that I, HERMAN D. KUHLMAN, a citizen of the United States, residing at Omaha, in the county of Douglas and 5 State of Nebraska, have invented certain new and useful Improvements in Lubricators, of which the following is a specification, reference being had to the accompanying drawings.

10 This invention relates to certain improvements in lubricators and has relation more particularly to a device of this general character embodying a force feed including a mechanically operated follower, and it is an 15 object of the invention to provide a novel and improved device of this general character including a cup provided with a filling opening and wherein a closing member contacts with the opening and is adjusted or 20 moved into open position by the follower during its retracted movement.

It is also an object of the invention to provide a novel and improved device of this general character including a follower 25 mounted for movement within a cup and wherein means is provided for effectively holding the follower against movement.

The invention consists in the details of 30 construction and in the combination and arrangement of the several parts of my improved lubricator whereby certain important advantages are attained and the device rendered simpler, less expensive and otherwise more convenient and advantageous for 35 use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a lubricator 45 constructed in accordance with an embodiment of my invention.

Fig. 2 is a view partly in section and partly in top plan of the device illustrated in Fig. 1.

50 Fig. 3 is a sectional view taken substantially on the line 3—3 of Fig. 1.

As disclosed in the accompanying drawings, C denotes a cup of requisite dimensions and provided in its bottom with a central discharge or reduction opening 1

through which grease or other lubricant is adapted to be forced. The interior walls of the cup C are smooth and unobstructed and the upper or outer end portion of the cup C is closed by a cap 2. Threaded through the 60 central portion of the cap 2 is a rod 3 having affixed to the inner end portion a follower or piston 4 so that upon rotation of the rod 3 in one direction the follower or piston 4 will be caused to move inwardly or 65 downwardly to effect the desired ejection of the lubricant within the cup.

A side wall of the cap 2 is provided with an opening 5 normally closed by the slide 6 having movement in a direction longitudinally of the cup C. The slide 6 is provided with an inwardly directed lug 7 with which the follower or piston 4 contacts when said follower or piston is retracted so that the upward or outward movement of the follower 75 or piston 4 serves to move the slide 6 into open position so that grease or other lubricant may be applied within the cup C inwardly of the follower or piston 4. After the lubricant has been applied within the 80 cup C the slide 6 is returned manually to its normal and closed position.

The rod 3 is threaded substantially its entire length and engaged therewith is a jam or locking nut 8 provided with an outstanding lever 9 whereby the requisite rotation may be imparted to the nut 8 as the occasions of practice may require.

After the slide 6 has been returned to its closed or normal position the lever 9 is 90 swung into a position to overlie the outer or upper edge of the slide to hold the same in closed position and said movement of the lever 9 also causes the nut 8 to tighten against the cap 2 to hold the rod 3 in position.

The outer end portion of the rod 3 is provided with a handle 10 or other means whereby the requisite rotation may be imparted thereto to cause the follower or piston 100 4 to move in the desired direction longitudinally of the cup C. When it is desired to move the follower or piston 4 upwardly or outwardly and to elevate or raise the slide 6, the lever 9 is swung sufficiently to free 105 the slide 6 and in order to limit the extent of this lateral swinging movement of the lever 9 the cap 2 is provided with an outstanding stop lug 11 with which said lever 9 contacts. The stop lug 11 also serves to hold 110

the nut 8 and lever 9 from rotating when the rod 3 is being rotated in a direction to move the follower or piston 4 upwardly or outwardly.

5 My improved lubricator as herein disclosed is primarily adapted for use in connection with locomotive crank pins, but I do not wish to be understood as limiting myself to this particular usage. It is also 10 to be understood that the follower or piston 4 fits snugly within the cup C.

From the foregoing description, it is thought to be obvious that a lubricator constructed in accordance with my invention is 15 particularly well adapted for use by reason of the convenience and facility with which it may be assembled and operated and it will also be obvious that my invention is susceptible of some change and modification 20 without departing from the principles and spirit thereof and for this reason I do not wish to be understood as limiting myself to the precise arrangement and formation of the several parts herein shown in carrying 25 out my invention in practice except as hereinafter claimed.

I claim:

1. A lubricator comprising a cup provided with a filling opening in a side wall, 30 a slide for closing said opening, a follower arranged within the cup, means for moving the follower in opposite directions longitudinally of the cup, said slide being provided with means whereby the follower upon

movement in one direction, moves the slide into open position.

2. A lubricator comprising a cup provided with a filling opening in a side wall, a slide for closing said opening, a follower arranged within the cup, means for moving the follower in opposite directions longitudinally of the cup, and an inwardly directed lug carried by the slide engaged by the follower upon movement in one direction for moving the slide into open position. 40 45

3. A lubricator comprising a cup having a filling opening in a wall thereof, a slide for closing said opening, a follower within the cup, a rod extending exteriorly of the cup for imparting movement to the follower in either direction longitudinally of the cup, and means carried by the rod for holding the slide in closed position. 50

4. A lubricator comprising a cup having a filling opening in a wall thereof, a slide for closing said opening, a follower within the cup, a rod extending exteriorly of the cup for imparting movement to the follower in either direction longitudinally of the cup, a nut threaded upon the rod exteriorly of the cup and provided with an outstanding lever, said lever in one position coacting with the slide for holding the same in closed position. 55 60

In testimony whereof I hereunto affix my 65 signature.

HERMAN D. KUHLMAN.
